FUEL CONTROL DEVICE

Merlin Hansen, Waterloo, Iowa, assignor to John Deere Tractor Company, Waterloo, Iowa, a corporation of Iowa

Application November 22, 1940, Serial No. 366,559

4 Claims. (Cl. 261—18)

The present invention relates generally to fuel control devices and has for its principal object the provision of a control mechanism in a fuel burning apparatus, for automatically shifting the control of the fuel feed from one type of fuel to another, responsive to an operating condition in the fuel burning apparatus. One embodiment of my invention relates to internal combustion engines for service under conditions in which the engine operates a majority of the time under substantially full load, but is required to idle during extended periods which occur rather infrequently, such as, for example, engines for propelling tractors and other vehicles. In this type of service, it is conventional to use an aspiration type engine with spark ignition, operating on a comparatively low cost fuel oil. With this type of engine it is customary to carry a supply of comparatively high grade, high cost fuel, such as gasoline, to make it possible to start the engine readily and run it until it is warm enough to successfully burn the lower grade fuel. Although many different types of engines can successfully burn fuel oil, when operating under a sustained substantially normal load, very few engines can be successfully operated at idling speed and without load, for the reason that the engine cools down appreciably, making it difficult to carburet the fuel oil, with the result that it is difficult to keep the engine running during a long period of idling. Furthermore, after a period of idling operation, it is difficult to load an engine of this type without stalling.

It is a further object of my invention, therefore, to provide an internal combustion engine which normally burns low cost fuel under conditions of normal load, but which can be idled successfully, and after a period of idling can be made to readily carry its normal load without stalling.

In the accomplishment of these objects I have discovered that if the fuel feed of the engine be switched from low grade to high grade fuel, as for example, the gasoline supply which is used for starting the engine, the engine will idle successfully for long periods of time and then can be loaded successfully and switched back to the lower grade fuel without danger of stalling. A further object of my invention, therefore, has to do with the provision of a control device, which will automatically shift the fuel feed from low grade to high grade fuel as soon as the engine begins to idle, and to automatically shift back to low grade fuel whenever the engine assumes its normal load once more.

It is desirable to operate the engine on gasoline for a short time after it is loaded after a long period of idling to permit the temperature of the engine to rise to the point at which efficient carburetion of fuel oil is obtained. It is a further object of my invention to introduce an apprecia-

ble delay between the change in load and a change in the type of fuel fed to the engine.

In the preferred embodiment of my invention I have provided a control device which is responsive to the pressure in the intake passage or manifold of the engine. When the engine is running at approximately full load, the throttle in the intake passage is nearly wide open and therefore the pressure in the passage is nearly equal to atmospheric pressure. When the engine is idling at no load, the throttle is nearly closed and the suction of the engine reduces the pressure in the intake passage or manifold to a partial vacuum, as is well-known to those skilled in the art. It is this change of pressure in the intake passage of the engine which is used in the preferred embodiment as a controlling factor for shifting the fuel feed from one fuel to the other.

These and other objects and advantages of my invention will be apparent to those skilled in the art after a consideration of the following description in which reference is had to the drawing appended hereto, in which

Figure 1 is a longitudinal sectional elevation of a device embodying the principles of this invention; and

Figure 2 is a transverse sectional elevation taken along a line 2—2 in Figure 1.

Referring now to the drawing, the internal combustion engine is represented by a carburetor 5 of any suitable type or construction, the details of which are not concerned with, and an intake passage or manifold 6, rigidly connected to the carburetor 5 by suitable bolt means 7, through which the carbureted mixture flows from the carburetor to the engine cylinders. A damper or throttle valve 8 is disposed in the intake passage between the jets of the carburetor (not shown) and the cylinders in order to control the rate of flow of the fuel mixture. The damper 8 is mounted on a vertical spindle 9 journaled in a boss 10 in the carburetor, and a control lever 11 is fixed to the upper end of the spindle 9, for the purpose of rotating the damper valve 8 within the intake passage. Liquid fuel is fed to the carburetor 5 through a duct 12.

The low grade fuel is supplied to the engine from a main fuel tank 15 through a fuel feed conduit 16, and the high grade fuel is supplied from an auxiliary fuel tank 17 through a duct or conduit 18. The high grade fuel from the tank 17 will be hereafter referred to as gasoline, since that is the type of fuel which is preferred for this purpose.

The feeding of the fuel oil and gasoline to the carburetor is selectively controlled by means of a fuel feed control device, indicated generally by reference numeral 20, comprising a housing 21, in the opposite side walls of which are supported a pair of opposed fuel valves 22, 23, respectively.

Each of the valves 22, 23 comprises a bushing 24, one end of which is threaded into an opening 26 in the side wall of the housing 21, and the other end of which is internally threaded to receive a valve fitting 28 having a central duct 27 terminating in a valve port 29 at the inner end of the fitting 28. A valve pin 29 is slideable axially within the bushing 24 and has a tapered end 30 which is adapted to fit into the valve port 29 to interrupt the flow of liquid fuel through the passage 27. Each of the fuel conduits 16, 18 is suitably coupled to the valve fittings 28, respectively, and a manually operated petcock 31, 32 is connected in series with each of the supply ducts 16, 18.

The two valve pins 29 are disposed in alignment on opposite sides of the housing 21 and are interconnected by a link 35 having downwardly turned ends 36 which are bifurcated to provide a slot 37 adapted to receive a stem 38 of reduced diameter rigidly fixed to the inner end of each of the valve pins 29. Each of the stems 38 is provided with a head 39 which fits between the downwardly turned end portion 36 and the body of the link 35. The link 35 is made of such a length that when either of the tapered ends 30 of the valve pins 29 is seated in its respective valve port 29, the other is unseated to permit the flow of fuel through the valve. Each of the pins 29 is of a triangular cross section to maintain it centrally within the bushing 24 but to provide passage for the liquid fuel through the bushing past the pin 29. Thus it is evident that by reciprocating the link 35 horizontally along the axis of the bushings 24, the valve can be alternately opened and closed to permit the flow of one or the other of the fuels, selectively. Specifically, when the link is moved to the right, as viewed in Figure 1, the right hand pin 29 is seated in the valve port 28, preventing the flow of gasoline through the duct 18, while the left hand valve pin 29 is unseated from the valve port 28 and permitting the flow of fuel oil from the main tank 15 into the housing 21.

The link 35 is reciprocated by means of an arm 40 pivotally mounted within the housing 21 on a pivot pin 41, one end of which is journaled in a suitable bearing member 42 mounted in the back of the housing 21, and the opposite end of the pivot pin 41 is journaled in a bearing member 43 which is threaded into a suitable aperture in the cover plate 44 of the housing 21 and thus is adjustable along the axis of the pin 41 to adjust the amount of end play of the latter. The cover 44 is rigidly attached to the housing 21 by suitable bolts 45. The upper end of the arm 40 is bifurcated to provide a pair of legs 46, which straddle the link 35, and each of the legs 46 is slotted at 47 to receive a trunnion 48 rigidly mounted on the link 35. Thus, it is evident that by rocking the arm 40 about the supporting pivot pin 41, the link 35 is reciprocated horizontally through the trunnion and slot connection with the arm 40.

The arm 40 is controlled by means of a rod 50, the end of which extends into a slot 52 in the lower end of the arm 40 and is pivotally connected to the latter by means of a pivot screw 51. The rod 50 is fixed to a diaphragm 53 by a rivet 54. The diaphragm 53 is clamped between a pair of circular sheet metal cups 55. Each of the cupped members 55 is provided with a flange portion 56 which extends radially outwardly and receives therebetween the diaphragm 53. One of the flanges 56 is then bent over the other to provide a secure support for the diaphragm 53.

and which is sealed against passage of gas or liquid from one side of the diaphragm to the other. The diaphragm case 55 is tightly secured by screws 57 against the plate 58 which is fixed to one side of the housing 21, and the housing wall, the plate 58, and the case 55 are provided with aligned apertures 59 through which the connecting rod 50 extends between the diaphragm 53 and the arm 40.

The opposite side of the case 55 is provided with a tubular connecting portion 60, the end of which is threaded to receive a fitting 61 which connects the tubular portion 60 to a duct 62. The duct establishes communication between the intake passage or manifold 6 of the engine and the pressure chamber 63 between the diaphragm 53 and the case 55.

The diaphragm 53 is constructed of a thin flexible material, preferably fibre or metal, and is adapted to move within the case 55 responsive to changes in pressure in the pressure chamber 63. A coil spring 64 is disposed within the tubular neck 60 and acts in compression between the duct fitting 61 and the diaphragm 53, tending to urge the latter toward the housing 21 and thus forcing the arm 40, through the rod 50, to swing in a clockwise direction about the pin 41, thereby closing the gasoline valve 23 and opening the fuel oil valve 22, as illustrated in Figure 1. This is the normal position of the control device 20, so that for normal operation under substantially full load the engine operates on fuel oil fed from the main fuel tank 15, through the valve 22 into the housing 21 and through the discharge duct 12 connected into the lower portion of the housing 21 and conducting the fuel to the carburetor 6. Inasmuch as the throttle valve 8 is nearly wide open during full load operation, the pressure in the intake passage 6 is nearly atmospheric and therefore there is not sufficient difference in pressure between the atmosphere and the intake passage to overcome the pressure of the spring 64. However, when the throttle valve 8 is closed, to idle the engine at no load, the suction of the engine creates an appreciable vacuum in the intake passage 6, thus reducing the pressure in the pressure chamber 63, whereby the fuel, which is under atmospheric pressure in the housing 21, forces the diaphragm 53 toward the right, as viewed in Figure 1, and thereby rocking the arm 40 about its pivot 41 to shift the link 35 toward the left. This closes the fuel oil valve 22 and opens the gasoline valve 23. The gasoline then mixes with the fuel oil in the housing 21, and a gradual changeover to gasoline operation is effected, so that by the time the engine has cooled down the fuel oil has been consumed and the engine runs on straight gasoline, on which fuel it is able to successfully idle an indefinite period.

As soon as the throttle 8 is opened to load the engine, the vacuum in the intake passage 6 is relieved and thereby allows the spring 64 to return the diaphragm 53 to its normal position and thereby shifting from gasoline back to fuel oil. By the time the fuel oil has replaced the gasoline in the housing 21 and duct 12, the engine is warm enough to operate successfully on fuel oil without danger of stalling.

In order to prevent the diaphragm 53 from fluttering back and forth due to momentary variations in pressure in the intake passage 6, the arm 40 is yieldingly held in either of the two positions by means of a toggle holding device including a short link 70 having a ball portion 71,

72 fixed at opposite ends thereof, respectively. The lower ball portion 71 is swingably seated in a bushing 73, which is screwed into an aperture 14 in the lower side of the housing 21. The ball portion 72 at the upper end of the link 70 is seated in a suitable recess 75 in the lower end of the arm 40 and is held firmly seated therein by means of a coil spring 76 disposed in a recess 77 under the ball portion 71. The action of the spring 76 tends to hold the arm 40 in either of its extreme positions and insures that the link 35 is not balanced for any appreciable length of time in an intermediate position in which both of the fuel valves 22, 23 are opened.

Having described one embodiment of my invention, I do not intend the invention to be limited to the exact details shown and described herein, for variations will be readily apparent to those skilled in the art after a consideration of this disclosure.

What I desire to protect by United States Letters Patent is set forth in the claims which follow.

I claim:

1. In an internal combustion engine of the aspiration type adapted to operate on either of two fuels and having conduits for supplying each of said fuels and an intake passage, a device for selectively controlling the feeding of one or the other of said fuels, said device comprising a housing having a mixing chamber, a pair of fuel valves supported by said housing and connected with said conduits, respectively, to control the flow of each fuel into said chamber, a discharge duct connected with said chamber for conducting fuel to said engine, a reciprocable member engaging said valves to open one of the valves and close the other when said member is reciprocated in one direction and vice versa, link means connected to said member for reciprocating the latter, a pressure responsive member connected to said link means, a compartment in which said pressure responsive member is reciprocably disposed, said compartment being disposed in communication with said intake passage whereby a drop in pressure in the latter causes said pressure responsive member to move in one direction to operate said valves and thereby changing from operation on one of said fuels to the other, and means for returning said pressure responsive member toward its normal position when the pressure in said intake passage rises beyond a certain value.

2. In an internal combustion engine of the aspiration type adapted to operate on either of two fuels and having conduits for supplying each of said fuels and an intake passage, a device for selectively controlling the feeding of one or the other of said fuels, said device comprising a housing, a pair of fuel valves supported thereby and connected with said conduits, respectively, to control the flow of each fuel into said housing, there being a mixing chamber in said housing for receiving fuel from said valves and a discharge duct for conducting fuel from said chamber to the engine, said valves being disposed on opposite sides of said housing and having opposed aligned stems movable longitudinally to open and close the valves, a reciprocable link within said housing interconnecting said stems and adapted to close one valve and open the other when said link is moved in one direction, and vice versa, an arm pivotally mounted in said housing and connected with said link to reciprocate the latter, a pressure responsive member connected with said arm,

a compartment in which said pressure responsive member is reciprocably disposed fixed to said housing in communication therewith, and duct means connecting said compartment with a part of the engine for controlling said pressure responsive member.

3. In an internal combustion engine of the aspiration type adapted to operate on either of two fuels and having conduits for supplying each of said fuels and an intake passage, a device for selectively controlling the feeding of one or the other of said fuels, said device comprising a housing having a mixing chamber, a pair of fuel valves supported by said housing and connected with said conduits, respectively, to control the flow of each fuel into said chamber, a discharge duct for conducting the fuel to said engine, said valves being disposed on opposite sides of the housing and having opposed aligned stems movable longitudinally to open and close the valves, a valve actuating member disposed between said stems and reciprocable to open and close said valves alternately to control the feeding of said fuels, selectively, an arm pivotally supported in said housing and connected with said valve actuating member to reciprocate the latter, a pressure responsive member connected with said arm, a compartment in which said pressure responsive member is reciprocably disposed, duct means connecting said compartment with the intake passage of the engine, whereby a drop in pressure in the latter causes said pressure responsive member to move in one direction to operate said valves and thereby changing from operation on one of said fuels to the other, and means for returning said pressure responsive member toward its normal position when the pressure in said intake passage rises beyond a certain value.

4. In an internal combustion engine of the aspiration type adapted to operate on either of two fuels and having conduits for supplying each of said fuels and an intake passage, a device for selectively controlling the feeding of one or the other of said fuels, said device comprising a housing having a mixing chamber, a pair of fuel valves supported by said housing and connected with said conduits, respectively, to control the flow of each fuel into said chamber, a discharge duct for conducting the fuel to said engine, said valves having opposed, aligned stems on opposite sides of the mixing chamber, a valve actuating member disposed in said chamber between said stems and reciprocable to open and close said valves alternately to control the feeding of said fuels, selectively, an arm pivotally supported in said mixing chamber and connected with said valve actuating member to reciprocate the latter, a compartment disposed in communication with said chamber, a pressure responsive member reciprocably disposed in said compartment and dividing the latter, means coupling one side of said pressure responsive member with said arm to actuate the latter, duct means connecting said compartment on the opposite side of said pressure responsive member with the intake passage of the engine, whereby a drop in pressure in the latter causes said pressure responsive member to move in one direction to operate said valves and thereby changing from operation on one of said fuels to the other, and means for returning said pressure responsive member toward its normal position when the pressure in said intake passage rises beyond a certain value.

MERLIN HANSEN.
